Inventor

Ollie P. Beard.

By Clarence A. O'Brien.

Attorney

UNITED STATES PATENT OFFICE.

OLLIE P. BEARD, OF HOLDEN, MISSOURI.

PUMP BASE.

Application filed July 7, 1924. Serial No. 724,683.

To all whom it may concern:

Be it known that I, OLLIE P. BEARD, a citizen of the United States, residing at Holden, in the county of Johnson and State 5 of Missouri, have invented certain new and useful Improvements in a Pump Base, of which the following is a specification.

This invention relates to new and useful improvements in attachments for pumps 10 and more particularly adapted to a base structure therefor.

One of the important objects of the present invention is to provide a pump base wherein the same includes complementary 15 movable sections which are adapted to be brought into engagement with the pump and secured thereto thereby bracing the pump.

A further object of the invention is to 20 provide a pump base which is simple in construction, inexpensive, strong and durable and furthermore adapted for the purposes for which it is designated.

Other objects and advantages of this 25 invention will become apparent during the course of the following description.

In the drawing wherein for the purpose 30 of illustration is shown the preferred embodiment of my invention:

Figure 1 is a cross sectional view of my 35 improved base showing the same in position upon a pump, and

Figure 2 is a top plan view of the pump 40 base.

In the drawing wherein for the purpose 45 of illustration is shown the preferred embodiment of my invention, the numeral 1 designates the frame of my improved pump base and the same is substantially rectangular in design and is adapted to be secured to the foundation or platform A by means of the fastening bolts 2. A flange 3 extends around the inner edges of the frame in the manner shown in Figure 1 and the purpose thereof will hereinafter be more fully described.

Adapted for slidable movement within the frame 1 and on the foundation or platform A are the complementary sections 4 and 5 respectively. The flange 3 retains the sections in proper position within the frame as is obvious from the construction shown in Figure 1.

The complementary sections are inclined 55 slightly upwardly toward the center of the frame and are provided with the substan-

tially semi-circular upstanding flanges 6 and 7 respectively, the same being adapted to encircle the pump B. Serrations such as are shown at 8 are arranged on the inner faces of the semi-circular flanges 6 and 7 respectively for engagement with a pump B so as to prevent the slipping of the flanges which encircle the pump. The flange C which is carried by the pump B will be disposed below the complementary sections 4 and 5 in the manner clearly illustrated in Figure 1.

For the purpose of holding the semi-circular flanges 6 and 7 of the complementary sections 4 and 5 respectively in engagement with the lower portion of the pump B, I provide the retaining ring 9 which extends over the pump B and around the semi-circular flanges 6 and 7 in the manner clearly illustrated in the drawing. The ring 9 is further provided with diametrically opposed openings in which are supported the thumb screws or bolts 10 and the inner ends of the bolts are adapted to engage the semi-circular flanges whereby the latter are moved into locking engagement with the pump B.

The provision of a pump base of the character above described enables the several parts to be readily moved into locked engagement with the pump and when in locked engagement will support the pump in proper position on the foundation or platform to which the same extends.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. A pump base comprising a substantially rectangular shaped frame, a flange formed on the inner edges thereof, a pair of complementary sections slidable in said frame beneath said flange, upstanding semi-circular flanges provided on the inner opposed edges of said sections and adapted to encircle a pump, and means for securing said sections in locked engagement with the pump.

2. A pump base comprising a substantially rectangular shaped frame, a flange formed on the inner edges thereof, a pair

of complementary sections slidable in said frame beneath said flange, upstanding semi-circular flanges provided on the inner opposed edges of said sections and adapted to encircle a pump, means for securing said sections in locked engagement with the pump, said means comprising a ring extending over the pump and around the afore-

mentioned semi-circular flanges, and thumb bolts threaded through said ring at diametrically opposite points and having the inner ends thereof engaging the semi-circular flanges. ¹⁰

In testimony whereof I affix my signature.

OLLIE P. BEARD.
